(57) **CLAIM**

The ornamental design for a cable support, as shown and described.

DESCRIPTION

FIG. 1 is a top right front perspective view of a cable support showing my new design;

FIG. 2 is a top left rear perspective view thereof;

FIG. 3 is a bottom left rear perspective view thereof;

FIG. 4 is a right side view, with the left side view a mirror image thereof;

FIG. 5 is a front view thereof;

FIG. 6 is a rear view thereof;

FIG. 7 is a top view thereof; and,

FIG. 8 is a bottom view thereof.

The broken line showing of environmental structure is for illustrative purposes only and forms no part of the claimed design.
